TRANSMITTING APPARATUS IN TELE-
PRINTERS

Reginald Dennis Salmon and Frank Reginald
Thomas, Croydon, England, assignors to Creed
and Company, Limited, Croydon, Surrey, Eng-
land

Application December 10, 1935, Serial No. 53,702
In Great Britain February 22, 1935

4 Claims. (CL. 178—23)

This invention relates to telegraph apparatus and more particularly to "answer back" devices. Such a device consists of a sleeve carrying a plurality of sets of cams, each set representing a character, which forms part of a teleprinter and is adapted to be automatically released on the receipt of a distinctive signal to cause the transmission of the characters represented by the sets of cams. These characters indicate the identity 5 of the station at which the teleprinter is located, usually a telephone exchange and number.

In such devices the cams representing the characters to be transmitted usually act directly upon a set of combination bars to control the transmission of the characters, as described in British Patent No. 351,018. If it be desired to transmit a considerable number of characters it has hitherto been necessary to make the sleeve carrying the cams of large diameter.

20 The present invention has for its object to enable cams representing a considerable number of characters to be placed on a sleeve of comparatively small diameter.

According to one feature of the present invention we provide telegraph apparatus of the kind referred to in which the sets of cams representing characters act upon the transmitting contact tongue through the medium of a series of pivoted levers brought into contact with said cams to be 25 positioned thereby and out of contact therewith for each character to be transmitted.

The cams representing the character may, by this means be made of small size, since they do not act on the levers to cause positive movement 30 thereof, but the levers merely feel the nature of the cams against which they are moved.

According to another feature of the invention, telegraph apparatus of the kind referred to comprises a pair of parallel shafts, one of said shafts 35 being automatically released for rotation on the receipt of a distinctive signal and driving the other of said shafts, which carries the said sleeve, in such a manner that the first mentioned shaft rotates a large number of revolutions for one 40 revolution of the second mentioned shaft, and cam means on said second mentioned shaft for maintaining the first mentioned shaft in rotation until the first mentioned shaft has completed one revolution.

50 In this way the diameter of the sleeve may be made small, since the main cam-controlled operations are performed by the shaft that rotates at the faster speed, and the cams that serve to carry out the various operations are less steeply 55 cut and therefore subject to less shock and wear

than if they were upon the slowly moved shaft.

One embodiment of the invention will be described with reference to the accompanying drawing in which

Fig. 1 is a cross section of the device, and 5

Figs. 2, 3, 4 and 5 are sectional elevations taken on the lines A, A, B, B, C, C, D, D, respectively. For the sake of clearness the various levers shown in Figs. 2 to 5 have been omitted from 10 Fig. 1.

Referring to Fig. 1, 25 is a spindle carrying a sleeve 26 upon which are mounted three cams 28, 29 and 30, a gear wheel 27 and a sleeve 33 carrying cams 32. Gear wheel 27 is driven via gear wheels 23 and 24 from gear wheel 22 mounted on a second spindle 36 driven from a friction clutch 19. Spindle 36 carries a detent 10 and three cams 18, 20 and 21. Lever 11 (Fig. 4) normally engages with detent 10 so as to arrest spindle 36. The upwardly extending portion of 20 lever 11 engages with cam 28. Lever 6 (Fig. 3) is controlled by cam 30 and also by cam 21. The lower portion of lever 6 extends across the five selector levers 4, the upper ends of which co-operate with cams 32 on sleeve 33. At their lower 25 end the levers 4 are acted on by springs 2 tending to move them into contact with the cams, and they are also adapted to engage with projections on transfer bars 3. Lever 5 is controlled by cam 30 and also by cam 20, and is acted upon at its 30 lower end by spring 7. It also carries at its lower end a pin engaging with another projection on transfer bars 3.

The gear ratio between spindle 36 and the sleeve 26 is such that the spindle 36 makes a large 35 fraction of a revolution, say a quarter of a revolution, whilst sleeve 26 rotates an amount equal to the pitch between the rows of cams on the sleeve 33; in the present case provision is made for 24 rows on the sleeve. A spindle 36 also carries a cam 18 co-operating with a lever 16 engaging with a bar 17. The bar 17 is adapted to release the clutch of the start stop transmitter, and bars 3 are adapted to control the signals sent out from this transmitter. 40 45

Lever 11 also carries an extension engaging with lever 13 which is under the control of the receiving mechanism, and an extension 9 engaging with a bar 8 adapted to prevent the depression of any key on the keyboard. 50

The operation of the device is as follows:—

Upon the receipt of the answer back signal on the receiving mechanism the lever 13 is operated, so causing the lever 11 to rotate in an anti-clockwise direction, thus releasing detent 10 and 55

allowing spindle 36 to rotate. As soon as spindle 36 commences to rotate, cam 28 on sleeve 26 engages with the upper end of lever 11, so preventing it from re-engaging with the detent 10. 5 The spindle 36 will therefore continue to rotate until the sleeve 26 has completed one revolution, when the upper end of lever 11 will be released, so as to permit it to rotate, and re-engage with the detent 10 on spindle 36, thus bringing it to rest. As spindle 36 rotates the cam 21 allows lever 6 to move to the left, thus releasing the five selector levers 4, and allowing them to press against the cams on the sleeve 33 which are presented to them. The cams are cut so as to set 10 the levers 4 under the action of their springs 2 in a manner corresponding to the letter to be transmitted. The movement of levers 4 control the setting of bars 3 and thus the operation of the transmitter. While levers 4 are being set 15 cam 18 acts to release the start stop transmitter through the medium of lever 16 and bar 17. After the five signals have been transmitted those bars 3 which have been moved to the left are reset to their right-hand positions by lever 5 under 20 the action of springs 7 controlled by cam 20. The timing is such that the start stop transmitter is arrested before the lever 16 under the action of cam 18, restarts it to transmit another character, and the cycle of operations just described 25 is repeated.

Under some circumstances it is necessary to prevent the levers 4 and 5 from interfering with the setting of bars 3 during the first portion of the revolution of sleeve 33; for example, through 30 an interval equal to four letter characters. For this purpose, the cams 29 and 30 are so cut that when levers 5 or 6 are released by cams 20 and 21 their upwardly extending portions will bear against the two cams 29 and 30 respectively, 35 and will be prevented from moving.

While the answer back device is in operation it is important to prevent the keyboard of the transmitter from being operated in order to prevent mutilation of the signals being sent out by 40 the answer back device. For this purpose the extension 9 on the lever 11 is adapted to maintain a bar 8 in engagement with the keyboard combination bars during the time the sleeve 26 is rotating. The bar 8 prevents the combination bars 45 from being moved, and thus prevents any key on the keyboard from being depressed.

In order that the cams 32 on the sleeve 33 may be readily changed they are held in slots in the sleeve 33 by flanged discs 31 and 34 by means of 50 a nut 35. The collar 34 has a single slot in it corresponding to one of the slots in the sleeve 33. Thus as the nut 35 is slackened the collar 34 may be turned so as to bring the slot in it opposite to any cam which may then be abstracted 55 and replaced. The collar is finally turned into such a position that the slot in it does not come opposite any cam and the nut is then reclamped.

What is claimed is:

1. In type printing telegraph apparatus, a shaft, means for automatically releasing said shaft for rotation on receipt of a distinctive signal, a sleeve carrying cams cut to represent a set of characters to be transmitted, reduction gearing on said shaft for driving said sleeve at a reduced speed, a set of adjustable combination bars for determining characters, means periodically contacting said cams for determining the adjustment of said combination bars for the transmission of signals, 10 a series of characters represented by said cams, and means for maintaining said shaft in rotation until all said signals have been transmitted and for arresting said shaft thereafter.

2. In type printing telegraph apparatus, a shaft, 15 means for automatically releasing said shaft for rotation on receipt of a distinctive signal, a sleeve carrying cams cut to represent a set of characters to be transmitted, means on said shaft for rotating said sleeve at a reduced speed, a set of 20 pivoted levers, one for each element of a signal, means on said shaft for reciprocating said levers against said cams once for each character to be transmitted, means for determining the transmission of a signal for each character represented by the setting of said levers by said cams, and means for maintaining said shaft in rotation until all said signals have been transmitted and for arresting said shaft thereafter.

3. In type printing telegraph apparatus, a set 30 of combination bars, means for setting said bars in various combinations to represent characters for transmission, a cam shaft for transmitting a start signal, followed by a series of signals determined by the setting of said combination bars, 35 a shaft, means for releasing said shaft automatically on receipt of a distinctive signal, a sleeve carrying cams cut to represent a set of characters to be transmitted, reduction gearing for driving said sleeve from said shaft, means on 40 said shaft for releasing said cam shaft for rotation for each character cut on said sleeve, and means on said shaft for setting said combination bars according to said cams on said sleeve.

4. In type printing telegraph apparatus, a set 45 of combination bars, keyboard means for setting said combination bars in various combinations to represent characters for transmission, a cam shaft for transmitting a start signal followed by a series of signals determined by the setting of 50 said combination bars, a sleeve carrying cams cut to represent a set of characters to be transmitted, means for automatically releasing said sleeve for rotation on receipt of a distinctive signal, means for reciprocating a set of pivoted levers, one for 55 each combination bar, against each set of cams representing a character to set said combination bars and means for releasing said cam shaft for rotation for each setting of said combination bars by said pivoted levers.
